UNITED STATES PATENT OFFICE.

FREDERICK H. SCHULENBERG, OF LIMA, OHIO, ASSIGNOR TO VAPO STOVE COMPANY,
OF LIMA, OHIO.

OIL VALVE.

Application filed February 7, 1922. Serial No. 534,786.

To all whom it may concern:

Be it known that I, FREDERICK H. SCHULENBERG, a citizen of the United States, residing at Lima, in the county of Allen, State of Ohio, have invented certain new and useful Improvements in Oil Valves; and I do hereby declare the following to be a full, clear, and exact description of the invention, such as will enable others skilled in the art to which it appertains to make and use the same.

This invention relates to new and useful improvements in valves and particularly to valves for controlling the flow of liquid or gaseous fuel. The particular adaptation of the valve is for oil- or gas-burning cook stoves.

One object of the invention is to provide a valve of this character having means for limiting the opening and closing movement thereof.

Another object of the invention is to provide a valve of this character having an adjustable stop for limiting the opening movement of the valve beyond the starting position or that position wherein the fuel is permitted to flow to the burner.

A further object is to provide a valve with which is associated a sight-feed having a priming means formed integrally therewith.

A still further object is to provide a novel valve of this character having a packing and a bushing so constructed and arranged that the packing can be forced into close embracing relation to the stem of the valve.

Other objects and advantages will be apparent from the following description when taken in connection with the accompanying drawing.

In the drawing:

Figure 1 is a top plan view of the valve and a portion of the pipe leading to a burner together with a portion of the fuel manifold.

Figure 2 is a vertical transverse sectional view on the line 2-2 of Figure 1, showing the valve and pipe in side elevation.

Figure 3 is a front elevation of the valve and priming device, the manifold being removed.

Figure 4 is a vertical sectional view

through the valve on the line 4-4 of Figure 1, which line is parallel to the line 2-2. 55

Figure 5 is a longitudinal sectional detailed view through the handle and locking plunger.

Referring particularly to the accompanying drawing 10 represents the body of the valve which has the fuel inlet passage 11 extending inwardly from one side and having the threaded nipple 12 for attachment to the fuel manifold 13. Formed vertically through the body of the valve is a passage 14, said passage being reduced to form the shoulder 15, on which rests the cylindrical packing 16. Engaged in the upper end of the passage 14, is a brass bushing 18, the lower end of which is inwardly and upwardly beveled as at 19, for engagement with the upper end of the packing 16 and by means of which said packing is compressed, upon downward movement of the bushing, to force the packing into close embracing engagement with the upper portion of the stem 20. This stem has its lower portion threaded into the passage 14, as shown at 21, and the lower end of the stem is formed with a tapered point 22 70 which seats in the conical seat 23. A portion of this seat is formed within the conical boss 24, which is formed integrally with the valve body and projects downwardly from the center thereof. 75

As clearly shown, the passage 11 communicates with the lower portion of the passage 14, so that when the needle valve stem 20 is elevated its point is unseated, and the fuel will pass downwardly and drop from the lower end of the boss 24. A cap nut 25 is screwed on the threaded neck 26, which is formed on the upper side of the valve body, and is arranged to drive the bushing 18 downwardly against the packing 16 when turned downwardly. The stem 20 is rotatably disposed through this cap. 90

Detachably secured to the upper end of the stem 20 is a laterally extending handle 27, the same being secured thereto by means of the screw 28. Secured to the upper face of the valve body, and receiving the neck 26 upwardly therethrough, is a dial plate 29, the same being slightly less than a complete circle. This disk is secured to the valve body by means of the screws 30. 100 105

Formed in the dial plate 29, adjacent one end of the flat edge thereof, is a depression 31, and at a point approximately 135° from the depression 31 is another similar depression 32. Extending radially from the attaching portion of the handle, at a point diametrically opposite to the handle is an arm 33, and formed on the outer end of this arm is a downwardly extending tubular member 34, within which is disposed the spring pressed plunger 35, the spring 35' of which normally urges the lower end of the plunger into contact with the upper face of the dial plate 29, said plunger being arranged to drop into the said depression 31 or 32 according to the position of the handle and valve stem.

Projecting from the lower end of the tubular member 34 is a nose 36, to which reference will be made later.

In the edge of the dial plate 29 are formed the series of notches 37, said series beginning at the depression 32 and extending around in a direction toward the flat portion of the edge of the plate and in a direction away from the depression 31. Engaged on the neck 26 for rotation is a collar 38, this collar being split and having its ends extending outwardly as shown at 39, and receiving therethrough a pivot pin 40, for supporting the L-shaped member or latch 41, disposed between said ends. The intermediate portions of the ends 39 are outwardly and oppositely bowed as at 42 to provide a tubular socket for the coil spring 43. The upper end of this coil spring bears against the lower face of the dial plate 29; while its lower end bears on the upper edge of the horizontal leg of the L-shaped member 41, to rock said L-shaped member and engage its vertical leg in one or another of the notches 37 on the dial plate.

Formed on the lower end of the valve body is a cylindrical boss 44, said boss being seated within the upper end of the sight-feed body 45. In the opposite sides of the upper end of the body 45 are formed the openings 46, and disposed within the body is a glass tube 47. Formed integrally with this body, and extending laterally and then curving upwardly, is the pipe 48, which has its upper end enlarged into the form of a cup or bowl 49. Into this cup or bowl 49 is adapted to be poured oil or gasoline for the purpose of priming the burner, with which the valve is used. A removable closure for this cup consists of a flat disk 50 having depending legs 51, which are so arranged as to rest within the mouth of the cup and hold the disk slightly elevated thereabove, to permit air to pass through the cup. Screwed into the lower end of the body 45 is the oil conveying pipe 52, which conveys oil to the burner.

In the operation of the device when the

plunger 35 is seated within the depression 31, the needle valve is firmly seated on the seat 23, thus effectively preventing the passage of oil through the valve. Upon lifting the plunger and swinging the handle toward the right, so that the nose 36 registers with the first of the notches 37, the plunger will drop into the depression 32. The needle valve is then unseated, but prior to this movement of the valve a priming charge of oil is poured into the cup 49 from whence it runs through the pipe 48 into the body 45, and thence through the pipe 52 to the burner, this oil being properly ignited in the burner by any well known means.

When the oil is burning, the valve is swung further so that the needle will be lifted higher from its seat, thus permitting more of the oil to flow through the passages 11 and 14, the oil flowing drop by drop from the end of the conical boss 24 through the body 45, where it can be seen through the openings 46, and thence to the pipe 52 and the burner.

When the proper flame is produced in the burner the L-shaped latch 41 is engaged in the proper notch 37, by rotating the collar 38 so that the nose 36 will engage therewith, thus limiting the opening movement of the valve. Then the operator may regulate the flame between its maximum and zero, by rotating the valve between the latch 41 and the depression 32. This latter position, however, is the minimum and when the valve is swung further in the direction of the depression 31 the flow of oil through the valve will be negligible until the plunger seats itself in the depression 31, when the flow will be stopped.

Attention is called to the fact that the depression 32 serves to prevent the complete cutting off of the flow of oil or gas to the burner, as when the handle has been set to some position between the depression and the latch, an accidental moving of the handle toward closing position will be prevented by the engagement of the plunger in the depression 32. Thus a child cannot turn out the flame, nor can the same be cut off by accidentally brushing against the handle.

What is claimed is:

1. In a liquid fuel valve, a valve body, an indicating disk on the body and having a portion of its periphery formed with a series of notches; a valve in the body having a handle on its upper end for traversing the dial, the dial having a depression, a spring pressed plunger carried by the handle and engageable in the depressions, a nose carried by the handle, and a spring pressed detent carried by the body and engageable in the different notches to be engaged by the nose of the handle.

2. In a liquid and gaseous fuel valve, a valve body, a dial on the body, the body having a neck, a collar rotatable on the neck, the periphery of the dial having a series of 5 notches, a spring pressed stop on the collar engageable in the different notches, a valve in the body, and means on the valve for

moving the valve and engageable with the stop.

In testimony whereof, I affix my signature 10 in the presence of a witness.

FREDERICK H. SCHULENBERG.

Witness:

W. M. HOFFMAN.
